UNITED STATES PATENT OFFICE.

WILLIAM LORD HALL, OF TROY, NEW YORK.

BOSOM-SHIRT.

SPECIFICATION forming part of Letters Patent No. 331,786, dated December 8, 1885.

Application filed February 2, 1885. Serial No. 154,652. (No model.)

To all whom it may concern:

Be it known that I, WILLIAM LORD HALL, of the city of Troy, county of Rensselaer, State of New York, have invented a new and 5 useful Improvement in Bosom-Shirts, of which the following is a specification.

My invention relates to bosom-shirts; and it has for its object the production of a cheap and simple means for attaching the bosom to 10 the shirt.

My invention consists in the combination, with a shirt-front that is made with a front re-enforce that has a bosom-opening cut out therefrom, of a bosom having an inner facing with 15 the edge of the opening cut in the re-enforce arranged to underlap the edges of the bosom and facing where adjacent, and a bias strip having turned-in side edges, said strip being laid exteriorly and then sewed through the 20 turned-in edge on one of its sides to and through the bosom, re-enforce, and shirt-front proper, and on its outer turned-in edge to and through the shirt-front proper and re-enforce, said strip covering the lapping edges of the 25 bosom and re-enforce.

Accompanying this specification to form a part of it there are two plates of drawings containing three figures illustrating my invention, with the same designation of its parts by 30 letter-reference used in all of them.

Of these illustrations, Figure 1 is a plan view of the re-enforce as cut out for the bosom and laid over the shirt-front proper, one of the upper inner corners of the re-enforce being shown as turned down. Fig. 2 illustrates the parts after the attachment of bosom and shirt has been made, they being shown as ripped apart on the line of their union, turned over and down at the top and one side 40 of the attachment. Fig. 3 shows a section taken on the line xx of Fig. 2, with the thickness of the parts exaggerated.

The parts of the shirt and those making the attachment of bosom and shirt are designated by letter-reference, and the process steps by which the attachment is made are described as follows: The letter S designates the shirt-body proper or shirt-front; R, the 45 re-enforce; B, the bosom; F, the bosom-facing; D, a bias-cut strip, and O an opening cut in the

re-enforce. The parts are attached by laying the re-enforce R over the shirt-front, then superimposing the bosom-facing and bosom, so that the edges of the opening cut in the re-enforce will underlap the coincidentally-laid edges 55 of the bosom and facing. To secure the parts thus laid before being sewed, they may be pasted, if desired. With the parts laid as thus stated, the bias-cut strip D is placed over the edges of the bosom and sewed through its turned in edge a' to and through the bosom, bosom-facing, and underlapping edge of the opening cut in the re-enforce, as indicated at m, and then the strip D is sewed through its turned-in side edge, a^2 , to and through the re-enforce R and shirt-front proper, as indicated at m, the strip covering the edges of the bosom, and being, as before described, on one of its turned-in edges sewed to and through the latter, the bosom proper, bosom-facing, and 65 underlapping edge of the re-enforce opening, and upon its other side edge through its turned-in edge a' to and through the re-enforce and shirt-body proper. The attachment thus illustrated and described is easily made, and it 70 thoroughly secures the parts.

Having thus described my invention, what I claim, and desire to secure by Letters Patent, is—

In an attachment for connecting a bosom to 80 a shirt, the combination of the re-enforce R, having an opening, O, with the edges of the bosom and bosom-facing both superimposed to overlap the edge of the re-enforce opening O, and a bias-cut strip, D, having turned-in 85 side edges, a' a^2 , which strip is sewed through one of its turned-in side edges to and through the bosom, bosom-lining, and underlapping re-enforce, and upon its other side edge through the latter, and to and through the re-enforce 90 and shirt-body, the said strip as attached covering the overlapping edges of bosom and facing, as shown and described.

Signed at Troy, New York, this 22d day of October, 1884, in the presence of the two witnesses whose names are hereto written.

WILLIAM LORD HALL.

Witnesses:

CHARLES S. BRINTNALL,
C. H. SHEPARD.
